FILLING FEELER FOR LOOMS

Edwin C. Smith, Providence, R. I., assignor to
 Rhode Island Warp Stop Equipment Company,
 Portland, Maine, a corporation of Maine

Application July 16, 1931. Serial No. 551,172

8 Claims. (Cl. 139—286)

My invention relates to improvements in filling feelers for looms of the side slip type so called; and the objects of my invention are, first to provide a filling feeler of the side slip type adapted for use with an electric stop motion to be introduced into the electrical stop motion circuit as a part thereof and to operate to close said circuit; and to provide means for regulating the elastic reaction of the side slip movement of the 10 feeler finger without varying the recoil resistance to pressure of the filling on the filling bobbin against the feeler finger due to movement of the loom lay in beating up the pick.

5 I attain these objects by means illustrated in the accompanying drawing, in which:

Fig. 1 shows, in plan view, my feeler with cover removed in conjunction with an unexhausted filling bobbin;

Fig. 2 shows, in plan view, my feeler with cover removed, and with feeler finger side slipped on an exhausted filling bobbin;

Fig. 3 shows a part sectional elevation in enlarged scale and on the line 3—3 of Fig. 1, looking in the direction of the arrow b; and

Fig. 4 shows an end elevation looking in the direction of the arrow c, Fig. 1.

The body 2, preferably of metal and made with the slot 3 for securing the feeler to the loom or to brackets attached to the loom, is made with a 30 channel or cavity 40 and guide-ways 4—4 in opposite sides of said channel and near its top. In these guide-ways is mounted a slide 5. Surmounting the slide 5 is a bearing plate 6 whose upper surface 7 is slightly above the top surface 8 of the body 2. A stud 9 fastens the slide 5 and bearing plate 6 together by its shank 10 which is preferably riveted to the slide 5. The stud 9 also holds in place the side slip feeler finger 11 which is free to swing on the body portion 12 of said 40 stud, and between the top surface 7 of the bearing plate and the flange or annular shoulder 13 of the stud. An upturned stop 14 on the slide 5 and in the path of movement of the heel 22 of the finger 11, limits the movement of the feeler 45 finger in the direction of the arrow d. The arrow d indicates the direction of reaction of the spring 15, encompassing the upper body 16 of the stud 9 and engaging the upturned projection of the heel 22 of the finger 11. The spring 15 is preferably of helical form and one end 17 of its wire 50 extends parallel with the spring's axis and engages the spring adjuster 18 secured to the top of the stud 9 by the screw 19 which enters a threaded hole in the top of the stud. The spring adjuster 18 which is of substantially disk form

with a depressed or dished center to adapt it to fit over the top of the stud 9 is perforated with a series of index holes 37 any one of which can be made to register with the lock pin 20 in the top of the stud. By loosening the screw 19, the cap 18 can be disengaged from the lock pin and turned to adjust the tension of the spring 15 and then replaced in engagement with said lock pin and secured by the screw 19 to hold the spring adjuster 18 to its lock pin and secure it to said stud 65 to hold the desired tension adjustment.

In the channel 40 within the feeler body 2 is a recoil spring 23 which is mounted on a pin 24. The pin is preferably a screw with a long straight body, a head 25 and a threaded extremity 26. 70 The pin passes freely through a down turned lug or ear 27 of the slide 5, and is threaded into an anchor plate 28 and secured by a check nut 29. The anchor plate 28 is mounted transversely of the channel 40, obstructing the guideways 4—4 75 and acting to limit the movement of the slide 5 and prevent it from protruding beyond the case 2. The recoil spring 23 holds the slide 5 against the head 25 of the pin 24 and thus maintains the feeler finger 11 projected toward the filling bobbin 80 31. The feeler finger 11 is thus projected away from the end of the slide 5 carrying the lug 27 and outwardly from the case 2 toward the shuttle box. The slide 5 and the finger 11 thereon are thus normally in position for the finger to be 85 encountered by the filling bobbin as the lay approaches the end of its forward movement toward the fell of the cloth. At the extremity of the finger is a tip of suitable material, usually some 90 form of fiber. This tip 36 meets the filling bobbin with an edge of irregular contour, usually serrated. This irregularity or roughening is embedded in the surface of the yarn of an unexhausted bobbin and prevents the finger from side 95 slipping when the bobbin and finger come together. When the filling has been exhausted and the tip encounters the smooth surface of the empty bobbin, it slides freely on that surface, the finger 11 being at such angle with the axis of 100 the bobbin as to cause the finger to yield and side slip, see Fig. 2. The finger 11 in side slipping, moves in the direction of the arrow f, which swings the upturned projection 21 of the heel 22 of the finger 11 into contact with the insulated contact spring 34. This contact spring 34 is carried on a terminal bracket 33 which in turn is held by an insulated mounting 32, and in such manner that the contact spring is in close juxtaposition to the projection 21 of the feeler finger 110

11, and to the spring end 39 which engages said projection.

It is common knowledge that the usual electric stop motion circuit has one side of said circuit 5 grounded in the loom frame or machine frame so that said frame with attached metallic parts is a part of the circuit thus constituting one open terminal. The other side of the circuit, in this 10 instance, is connected with the terminal by a circuit wire 35, so that when the feeler acts as described, by side slipping of the finger 11, the circuit is closed causing action of the stop motion. It is to be understood that all parts of my invention 15 are of metal or electro-conductive material except as otherwise specified.

A cover 38 combines with the body 2 to form a case, enclosing the spring contact 34 and all other working parts except the finger 11 and its tip 36. Wherever there is reference in the claims 20 to parts or combinations of parts being enclosed in the case, it is to be understood that reference is to the combined body and cover.

By the foregoing described invention I secure a feeler of compact construction, effective action 25 and sensitive response to varying yarn conditions and embodying within the feeler electrical contacts whereby the feeler is adapted to use with stop motion circuits and with the open contacts and moving parts protected from dirt and damage.

Without limiting myself to the precise construction shown and described, I claim:

1. In a side slip feeler-device for looms, the combination of a side slip finger, a slide having a 35 stop, a case within which said slide moves and from which said finger projects, a spring within the case for moving the slide to project said finger as aforesaid, a stud secured to the slide on which the finger swings, which stud has a flange spaced 40 from the slide and a body portion above said flange, the finger being mounted between the slide and the flange, a helical spring mounted on said body portion of the stud and engaging said finger, a substantially disk-shaped spring adjuster 45 mounting the stud and engaging the spring to force the finger against the stop on the slide, and means to secure said spring adjuster to said stud.

2. In a finger unit for a side slip feeler-device, 50 the combination with a side slip finger and slide to carry the finger, of a stud secured to the slide and permanently securing the finger to the slide, said stud being provided with a flange to hold said finger and with a body rising above said flange, a substantially disk-shaped adjuster having a recessed center portion fitting the top of said stud, a spring disposed about the body of the stud and engaging both finger and adjuster, means to lock the adjuster in whatever position 55 it may be turned to vary the tension of the spring, and means to secure said adjuster in locked position.

3. In a finger unit for a side slip feeler-device, 60 the combination of a slide, a stud secured to the slide and having a fixed flange spaced from the slide and a body portion rising above said flange,

a side slip finger permanently secured to the slide by said stud and movable between the slide and the flange, a spring coiled about the body of the stud with one end engaging the finger, an index pin in the top of the stud extending parallel with its axis, a spring adjuster having a recessed center which fits over the top of the stud, said adjuster being formed with a series of index holes to engage the pin and determine the adjustment of the spring, and means to secure said adjuster to the top of said stud to hold it in indexed adjustment.

4. In a finger unit for a side slip feeler-device, 65 the combination of a slide having a stop, a bearing plate, a stud secured to both slide and bearing plate, said stud having a flange spaced from said bearing plate and a body above said flange, a side slip finger movably mounted on said stud between its flange and the bearing plate, a spring coiled about the stud above its flange to hold the finger against the stop of the slide with resilient resistance, a spring adjuster having a dished center portion fitting the top of the stud and engaging said spring, means to lock said adjuster in any given position in adjusting the tension of said 70 spring, and means to hold the adjuster in adjusted position and secure it to the top of said stud.

5. A stud for mounting the side slip finger of a feeler-device, said stud formed with a bearing 75 for said finger, a bearing for a spring, a flange between the two bearings, and a projection extending from the top of the spring-bearing portion of the stud parallel with the axis of said stud.

6. In a spring adjusting device for a side slip 80 feeler, the combination of a stud having an axial threaded hole, a spring mounted on said stud, a substantially disk-shaped adjuster having a hole to receive one end of the spring, a circularly disposed series of index holes and a central hole, an index pin mounted in the end of the stud to engage one of the index holes in the adjuster, and a screw passing through the center hole of the adjuster and engaging the threaded hole in the stud to hold the adjuster to its index pin and to 85 the top of the stud.

7. A spring adjuster for a side slip feeler-device, 90 said adjuster having a dished body portion with a flat rim projecting radially therefrom in a plane substantially parallel with the plane of the bottom of said dished portion, the bottom of said dished portion being perforated with a central hole and circumjacent index holes, the axes of all 95 said holes being of substantially parallel direction and the rim provided with means to secure one end of the spring to be adjusted.

8. A spring retainer for a side slip feeler-device, 100 said retainer being formed with a dished body portion and a radially projecting flange located in a plane substantially parallel with the plane of the bottom of the dished portion and having provisions for securing one end of the spring to be 105 retained, the bottom of the dished portion being 110 perforated with holes for securing the retainer.

EDWIN C. SMITH.
